CABLE JOINT INSULATING MOLD

Norman E. Benson, Westport, Conn., assignor to The Acme Wire Company, Hamden, Conn., a corporation of Connecticut

Application October 22, 1956, Serial No. 43,448

Term of patent 14 years

(Cl. D26—10)

Fig. 1.

Fig. 2.

Fig. 3.

Fig. 4.

Fig. 1 is a perspective view of a cable joint insulating mold showing my new design;

Fig. 2 is a top plan view thereof;

Fig. 3 is a side view; and

Fig. 4 is a transverse section substantially on line 4—4 of Fig. 3.

I claim:

The ornamental design for a cable joint insulating mold, substantially as shown.
